UNITED STATES PATENT OFFICE.

CLARENCE C. SHIPP, OF INDIANAPOLIS, INDIANA.

AUTOMATIC AIR-RELEASE AND HUMIDIFIER FOR RADIATORS.

1,288,237.

Specification of Letters Patent. Patented Dec. 17, 1918.

Application filed January 11, 1917. Serial No. 141,869.

To all whom it may concern:

Be it known that I, CLARENCE C. SHIPP, a citizen of the United States, residing at Indianapolis, in the county of Marion and 5 State of Indiana, have invented certain new and useful Improvements in Automatic Air- Releases and Humidifiers for Radiators, of which the following is a specification.

This invention relates to a device for automatically exhausting air from steam and hot water radiators, to accelerate the action 10 of heat radiation, and also for exhausting amounts of water from time to time as may be required for humidifying purposes. 15 One of the objects of the invention consists in the provision of a device of the above character in which, when the radiator is out of operation, the shrinkage of the cooling water will sufficiently lower the water level 20 within the catch-pan, with a corresponding reduction in the elevation of the float, as to cause the valve attached to said float to be unseated, thereby allowing any subsequent accumulation of air within the radiator to 25 be discharged when the latter is again set into operation.

A further object of the invention consists in the provision of means whereby the discharge of air and water from the radiator 30 is controlled by the amount of discharged water accumulated in the humidifying water catch-pan.

I accomplish the above objects of the invention, and such others as may appear from 35 a perusal of the specification and claim, by means of the construction illustrated in the accompanying drawings, forming a part hereof, in which—

Figure 1 is a view partly in section and 40 partly in elevation of the mechanism for controlling the outflow of air and water discharged from the radiator. Fig. 2 is an enlarged detail sectional view through the end of the air and water discharge pipe. Fig. 3 45 is a fragmentary detail in side elevation of a radiator showing the position and application of my invention. Fig. 4 is an end elevation of the construction shown in Fig. 3.

Referring to the drawings, 10 represents 50 the several coils or sections comprising a conventional style of a steam and hot water radiator, in which each coil is provided with a vertically extending centrally arranged opening 11. To meet modern heating requirements which, among other things, necessitates the maintenance of a certain

amount of humidity within a room, I provide means consisting of a water catching and storing pan 12 which is open at its top to permit free escape of vapor into the room, and for convenience and to prevent marring the appearance of the radiator pan 12 is introduced into the openings 11 in the radiator coils. In order to insure constant operation of the humidifying apparatus and to accelerate the action of heat radiation, by the liberation of air from within the radiator, I introduce an automatic regulating device which not only removes the accumulated air from within the radiator but automatically maintains a sufficient supply of water in catch-pan 12 at all times for meeting the constant demands in maintaining the requisite percentage of moisture.

To accomplish the several objects heretofore noted, I establish communication with the interior of the radiator through the usual aperture 15, generally containing one of the many forms of air releasing devices, by means of an elbow 16 which communicates with a small hollow tube 17, the latter extending downward into the catch-pan 12 where it is coiled to form a hollow chamber 18. Examining Fig. 1, it will be noted that tube 17 is of small diameter and is formed

85 into a series of closely arranged spiral convolutions which will yield more or less when subjected to the influence of internal air pressure, thereby allowing gradual and silent exhausting of the air discharged from 90 the radiator into chamber 18. One of the objects in forming the convolutions in tube 17 is that after the air has been exhausted from the radiator, the subsequent flow of

95 vapor will be condensed to water before its discharge into valve chamber 20. As the air and water are discharged from tube 17 they pass into a valve-chamber 20 located in valve-housing 21, and in chamber 20 a valve 22 operates to control the flow of both the air 100 and water. Presuming valve 22 to be unseated from its valve seat 23, the water passes from valve-chamber 20 upward along valve-stem 19 and into the hollow portion of cylinder 36 from which it escapes into 105 pan 12 through an aperture 42 in valve-housing 21. The air passes upward past valve 22 and out through a small tube 25 which extends vertically into chamber 18. The upper end of chamber 18 is closed by 110 means of a plug 26 which is partly socketed to form a chamber 27 and the latter is

closed at the top by means of a cap-screw 28. Tube 25 extends upwardly through chamber 18 and plug 26 and has its discharge end at the floor line of chamber 27. The discharge end of tube 25 is normally sealed against inward flow of air or water into the radiator by means of a gravity seated spherical ball 30, the ball being induced to seat itself through the inclined formation of the bottom of chamber 27. Air is allowed to flow out of chamber 27 into chamber 18 through an aperture 31 in plug 26. As the air discharging into chamber 18 is more or less under pressure, the buzzing and sizzling noises usually accompanying such discharge are eliminated by the cushioning effect of the convolutions in tube 17, the said convolutions being sufficiently sensitive to yield under the influence of internal pressure, thereby causing the convolutions to spread and allow the air to gradually pass out from between said convolutions to the atmosphere. When sufficient water has accumulated in pan 12 to raise the water level a sufficient height to elevate float 35 the latter elevates and seats attached valve 22 so that further discharge of water and air is temporarily discontinued. Float 35, if desired, can be inclosed within a cylinder 36 which is supported by the valve-housing 21. The upper end of cylinder 36 is closed by means of a cap 37 having a recess 38 adapted to receive a pin 39 on the end of float 35 for guiding the latter in a determined path of travel. To prevent a partial vacuum being

created within the upper end of cylinder 36 the latter is provided near its upper end with an air vent aperture 40. When the water level within catch-pan 12 has been lowered to a point to no longer sustain float 35 the latter descends, causing valve 22 to be unseated and the discharge of water into pan 12 to be re-established.

Having thus fully described my said invention, what I desire to secure by Letters Patent is—

In combination, with a steam and hot water radiator, a pan for receiving the water discharged from said radiator, an air and water conductor-means communicating with the interior of the radiator and having its discharge in advance of a controlling valve, said conductor-means being provided with a series of convolutions for condensing vapor and for providing a chamber for receiving the exhausted air from the interior of the radiator, an air conductor-means extending from the rear of said valve and discharging into said chamber, means for closing the discharge end of said second conductor-means against back flow of air, a valve for controlling the outward flow of air and water from the radiator, and means actuated by the rise and fall of the water within said pan for seating and unseating said valve.

In witness whereof, I have hereunto set my hand and seal at Indianapolis, Indiana, this 30th day of December, A. D. one thousand nine hundred and sixteen.

CLARENCE C. SHIPP. [L.S.]
